UNITED STATES PATENT OFFICE.

EDWARD E. KLEINSCHMIDT, OF BROOKLYN, NEW YORK, ASSIGNOR, BY MESNE ASSIGNMENTS, TO MORKRUM-KLEINSCHMIDT CORPORATION, OF CHICAGO, ILLINOIS, A CORPORATION OF DELAWARE.

PRINTING TELEGRAPHY.

Application filed January 21, 1922. Serial No. 530,880.

To all whom it may concern:

Be it known that EDWARD E. KLEINSCHMIDT, a citizen of the United States, and resident of Brooklyn, in the county of Kings and State of New York, has invented certain Improvements in Printing Telegraphy, of which the following is a specification.

This invention relates to printers of the page- or tape-printing type for use in printing telegraphy. The ideal printer would be the one in which the mental functions of the human operator are performed by the electric current, while the mechanical functions are brought about by suitable power mechanism.

A copending application, Serial Number 390,598, filed June 21, 1920, discloses a telegraph printer in which an effort is made to approach this ideal. This application includes principally improvements in typewriter actions, complying to the peculiar requirements of a telegraphic type-bar printer and its various functions.

The present invention utilizes typewriter actions similar to those disclosed in the foregoing application, but operated by a single common power magnet, and controlled by electro-magnetic means actuated by electric impulses originating at a remote station. It is distinctive from telegraph printers, operated by constantly driven power mechanism, in that a single electro-magnet is employed for bringing about all the mechanical functions of the different typewriter actions, which electro-magnet is normally de-energized, and is energized only momentarily for each of the different printer operations. The advantages of the employment of such an electro-magnet, preferably in the form of a solenoid, include the feasibility of using either direct or alternating current, and the extreme simplicity of electric control of the different mechanically operating devices.

Another feature of the invention consists in the performance of the various typewriter functions by positive operation, including the restoration of operated parts.

A further feature refers to the arrangement of selector bars that remain in the position to which they are moved, and are moved to different positions only by positive action. They may be arranged in group

positions of predetermined characteristics, and remain in the selected group position, 55 until regrouped, without returning to normal position.

Other objects of the invention will appear in the disclosure, without being particularly referred to in this statement of 60 invention. The drawings show in Fig. 1, a longitudinal sectional elevation of the improved printer; Fig. 2, is a plan view of the selecting unit of the same; Fig. 3, a front elevation of the selecting unit, shown in 65 Fig. 2; Fig. 4, a perspective view, on an enlarged scale, of the left hand portion of Figs. 2 and 3, including one of the selector-magnets and the parts controlled thereby; Fig. 5, a perspective view, on an enlarged 70 scale, of the setting means for the selector bars; Fig. 6, a diagram of the circuits and the electro-magnetic devices controlled thereby; Fig. 7, a perspective view of the rear of the printer, showing particularly the mechanism for the different typewriter functions; Fig. 8, a side elevation of the spacing mechanism proper; Fig. 9, a plan view of the ratchet of the spacing mechanism; Fig. 10, a plan view of the rack-and-pinion of the 80 spacing mechanism; Fig. 11, a side elevation of the carriage-shift mechanism; Fig. 12, a side elevation of the shift-release mechanism and part of the line-feed mechanism; Fig. 13, an enlarged perspective detail of a portion of Fig. 11; Fig. 14, a side elevation of the carriage-return mechanism; Fig. 15, a side view of the carriage-return pull-bar, and Figs. 16 and 17, perspective views of details of construction of parts, shown in 85 Fig. 14.

Circuit arrangement.

Referring, first, to Fig. 6, of the drawings, 10 is a pair of line wires in which there is 95 arranged a polar magnet 11, provided with an armature 12 which is connected to a source of electrical energy, such as a battery 13. Any other generator of electrical energy, either direct or alternating, may be employed. The armature 12 may engage either one of a pair of contacts 14 and 15, in the usual manner, depending upon the character of the impulses received over the line. The contact 14 is connected through a conductor 16 to 100 a continuous ring 17 of a rotary distribu-

tor, indicated, in general, at 18. This distributor includes a ring 19, consisting of a plurality of insulated segments or contacts 20, of which there are five in the well known 5 Baudot printing telegraph system, to which the present invention is peculiarly adapted. A rotating brush 21 bridges the rings 17 and 19. The contacts 20 are connected, respectively, to selector magnets 22, and included in the circuit of battery 13. The circuits of selector magnets 22, therefore, are controlled by contacts 20 and rotating brush 21 and if, when this brush glides over a contact, armature 12 of line magnet 11 is in 10 engagement with contact 14, a corresponding selector magnet 22 will be energized, on the other hand, should at this time, armature 12 be in engagement with contact 15, the selector magnets will remain deenergized, all of which being now well known and old in the art.

The distributor 18 is provided with a second rotating brush 23, which engages a continuous ring 24, also connected to source of 25 electrical energy 13. Brush 23 bridges ring 24 with another ring 25, having a single insulated segment 26, the sixth impulse contact, with which brush 23 is brought into engagement, after brush 21 has passed all 30 five contacts 20 of ring 19, and the selecting impulses have been received. Contact 26 is connected to a magnet 27, which is also included in the circuit of battery 13, and its armature 28 is adapted to close a pair of 35 contact springs 29 and 30, controlling the circuit of a single operating solenoid 31 and its source of energy. A capacity 32 and a resistance 33, are preferably bridged between contacts 29 and 30, in the usual way, 40 in order to prevent sparking.

Selector unit.

The selector unit is shown in Figs. 2, 3, 4 and 5, and comprises a base plate 34, upon 45 which there are mounted frame plates 35 and 36, between which are arranged the selector magnets 22. These magnets are provided with armatures 37, pivoted at 38 and have their ends 39, remote of the magnets, 50 extending to positions beneath the lower arms 40, of the pawls 41, pivoted at 42, to the vertically displaceable pawl carrier 43. The ends of carrier 43 pass through slots in frame plates 35 and 36, and are provided 55 with rollers 44 and 45, adapted to be engaged by cam faces 46 and 47, of a longitudinally slidable actuating bar 48. One end of bar 48 carries a roller 49, adapted to be engaged by a wedge head 50, at the end 60 of a rocking arm 51, secured to an operating shaft 52, whereby a thrust roller 53, assists head 50, when engaging roller 49. A spring 54, tends to pull bar 48 toward the right, and springs 55, 56, pull pawl carrier 43 65 downward. Associated with each of the

pawls 41, there is a latch 57, pivoted on carrier 43 and connected to its proper pawl by means of a spring 58.

A stationary bar 59, supported in frames 35, 36, carries a tripartite lever 60 for each 70 pawl 41, of which the downwardly projecting arms 61 and 62, are adapted to be engaged by the upwardly extending arms 63, 64, of pawls 41, while an upwardly extending arm 65, engages a recess 66, on the lower 75 edge of a slideable selector bar 67. Selector bars 67 will remain in the position where last set until the position is changed in a succeeding selection, there being no normal position such as is common in the prior art. 80 In the embodiment shown, employing the Baudot code, there are five such selector bars, one for each selector-magnet 22, the functions of which are well known in the printing telegraph art. The selector bars 85 67 are provided, on their upper edge, with grooves 68, for receiving the pull bars 69.

The armature 37, of each magnet 22, is provided with a downwardly extending arm 70, adapted to be engaged by one end of a 90 latch 71, the opposite end of which is controlled within an elongated slot of a release bar 72. The bar 72 carries at one of its ends a dog 73, and near this end a second dog 74, the first to be operated upon by an arm 76, 95 of armature 28, and the second one to engage a latch 75, for holding another arm 78, of armature 28. A helical spring 79 holds armature 28 away from its electro-magnet 27, and another spring 80 holds latch 75 100 toward arm 78. Individual springs 81 hold each of the latches 71 toward the arms 70.

The normal position of parts, before any selection takes place, is shown in Fig. 3. Bar 48 is in its extreme left position, under 105 tension of spring 54, and its dog 84 is held by pawl 85. The armature 28, of magnet 27, is prevented to occupy its attracted position, through the locking of arm 78, by latch 75, 110 under tension of spring 80. The pawl carrier 43 is in its lowermost position under tension of springs 55 and 56, and rollers 44, 45, rest in cam faces 46, 47, of operating bar 48. Pawls 41 are all tilted to the right, 115 their arms 40 in the extreme low position and in contact with the rear extensions of the unattracted armatures 37, latches 57 are tilted to the right and their lower locking faces in engagement with the upper locking faces of the right hand extensions of pawls 120 41, under tension of connecting springs 58, Fig. 3. A spring 77, Fig. 1, holds armature 37 of each selector-magnet 22 away from the magnet core. Stationary bar 59, carrying the tripartite levers 60, is provided with lugs 83, adapted to be engaged by a wedge 125 face of latches 57. Actuating bar 48 is provided with a dog 84, adapted to be engaged by pawl 85, secured to shaft 86. A crank arm 87 connects this shaft, by means of link 130

88, to crank arm 89, of shaft 90, of armature 28.

It will be apparent that until a selecting impulse is received by at least one of the 5 magnets 22, armature 28 will be mechanically locked by pawl 75 and no operation will occur in the printer; the first act in the reception of signals from the transmitter is the selective energization of magnets 10 22, resulting in the attraction of their respective armatures 37. The rear ends 39, of these armatures, are lifted by whatever magnets received an impulse, and the corresponding pawl 41 is tilted to the left. 15 Pawl 41 and its latch 40 change their respective locking faces and occupy the position, shown in Fig. 4, the upper locking face of latch 40 now engaging the lower locking face of pawl 41. The armature of the 20 magnet, first energized, locks its lever 70 to latch 71 which moves bar 72 to the right and causes the disengagement of latch 75 from arm 78, by means of dog 74. Magnet 27 is now ready to receive its energizing impulse, 25 called the sixth impulse, as soon as commutator brush 23 reaches segment 26, of the distributor head, after brush 21 has passed all five segments 20, and thereby transferred the incoming selecting impulses to magnets 30 22.

When the impulse over segment 26 is received at magnet 27, armature 28 is attracted, in consequence thereof pawl 85 is lifted from dog 84, and cam bar 48 pulled to the 35 extreme right by spring 54. Pawl carrier 43, is lifted by its rollers 44 and 45, rising from the lowest point of cam faces 46 and 47, now moving under them to the right, to the upper edge of cam bar 48, resulting in a tilting 40 to the right of vertical lever arm 65, of tripartite lever 60, and a corresponding shifting to the right of one or more of the selected selector bars 67.

After the shifting of the selector bars by 45 the prongs 63 and 64 of the pawls 41 has been effected, the wedge faces of latches 57 engage restoring lugs 83, forcing the latches 57 to the right in Fig. 4 about their pivots until the actuated ones of the pawls 41 are 50 freed from engagement with the corresponding ones of latches 57 and are permitted to restore to unactuated position as shown in Figs. 3 and 4.

It will thus be seen that in case a selector 55 bar has been shifted into selected position by a prior impulse and is selected again by a succeeding selecting impulse, no shifting of the bar is required. The pawls, however, of the non-selected magnets and having their 60 pawl arms 64 in engagement with right lever arms 62, will tilt levers 60 to the left and thereby restore selector bars 67 to normal non-selected position.

As now well known in the art, notches 68 65 in selector bars 67 are so arranged that, un-

der the action of selecting magnets, certain predetermined notches will be aligned, capable to receive the front end of pull bars 69, of the typewriting mechanism.

Simultaneously with the movement of cam bar 48, arm 76 of armature 28 pushed dog 73 to the left, operating all the latches 71 and releasing all selected armatures 37, under the pull of their springs 77, to their normal unattracted position. The movement of armature 28 also results in closing contacts 29, 30, and the circuit for the energization of solenoid 31, which, in turn, rocks operating shaft 52, and forces wedge head 50 between rollers 49 and 53, returning cam bar 48 to its normal position, for reengagement of its dog 84 with pawl 85.

Operating mechanism.

When magnet 27 is energized and its armature 28 attracted, as stated before, contacts 29, 30, were operated to close the circuit for solenoid 31. This solenoid is provided with a core 91, which rocks operating shaft 52, by means of link connection 92 90 and an arm 93, keyed to shaft 52. The operating frame, comprises rocker arms 94 and two spaced-apart parallel bars 95, 96, connecting the same, of which bar 95 is preferably roller-shaped and normally located 95 beneath lugs 97, formed on the lower side of pull bars 69, as rear extensions of arch-shaped recesses 98, while 96 is a universal bar, having a substantially rectangular edge, adapted to engage the lugs 97 and push any pull or actuating bar 69 forcibly toward the front of the machine.

The roller bar 95, normally located underneath lugs 97, prevents pull bars 69 to fall in notches 68 of selecting bars 67. As soon, however, as solenoid 31 rocks shaft 52, roller 95 aligns with arches 98 and permits a pull bar 69, that finds its notches 68 aligned, to drop in the aligned notches, whereby its lug 97 enters the path of movement of the universal bar 96, so that bar 69 is forcibly moved or actuated. In this manner it will be apparent that the pull or actuating bars 69 are permitted to drop easily into place, thus obviating objectionable noise and shock common in usual prior art machines. The universal bar 96 completes the printing stroke on its forward movement, and remains in engagement with the pull bar until a printed impression has been made. Pressure is therefore applied to the type-bar until a printed impression has been made on the paper. In previous printers it has been commonly the custom to cease application of pressure to the type-bar before impression was made. Dependence was placed upon inertia of the moving parts to complete the stroke and print. This results in objectionable shock, clatter and strain due to rapidly repeated blows. By use of the 130

mechanism shown, adjustment of tension of the spring 138, strength of the solenoid 31, and application of pull to the type-bar until an impression has been made, the objectionable noise and strain may be greatly reduced and practically eliminated.

Each of the pull bars 69 is linked to a vertical arm 99, by means of a pin 110 and the vertical arms, in turn, are linked to type bars 112, the latter pivoted at 113 and normally resting on type bar pad 114. The printing face of each type bar 112, at the end of the printing stroke, enters type bar guide 115 and forces type ribbon 116 against the printing page, supported on printing platen 117. Pull bars 69 are returned to normal position by means of helical springs 118. There is a pull bar provided for each letter of the alphabet, numeral or figure, as now well known in the art, and for each function to be performed by the printer.

Spacing mechanism.

The operation of any one of the type bars 25 actuates the spacing mechanism, as follows: Each of type bars 112 is provided with a shoulder 119, which, when the type bar is raised, engages universal bar 120, pivoted at 121 to vertical rocking supports 122, Figs. 30 1 and 8, normally biased by spring 123. One of the supports 122 is connected, by means of link 124, to lever 125, secured at its upper end to shaft 126. The free lower end of lever 125, Figs. 7 and 9, engages pawl lever 35 127, pivoted at 128, and in moving it, causes pawl 129 to glide over one tooth of ratchet 130 and engage the same so that on the return movement of lever 127, ratchet 30 will be advanced the distance of one tooth. A 40 retaining pawl 131 pivoted at 128 independently of lever 127 is normally held in engagement with ratchet 130 by means of a spring interposed between pawls 129 and 131 which also holds pawl 129 in engagement 45 with ratchet 130. It will accordingly be seen that pawl 131 prevents backward rotation of the ratchet 130. An arm 132 is pivoted to lever 127 at 133 and is bifurcated at its end, to engage arm 134, fastened to rear 50 operating shaft 135. This shaft is rocked by rocker arms 94 of front operating shaft 52, connecting rod 136 and crank arm 137 of shaft 135. At the time that bifurcated arm 132 is moved towards arm 134, the latter is rocked away from it, through the action of 55 solenoid 31.

When now this solenoid is deenergized, all the parts operated by its core armature are 60 returned to normal position, by means of spring 138. When the parts are thus returned, arm 134 engages forked arm 132, moving lever 127 and causing pawls 129, 65 131, to rotate ratchet 130 the distance of one tooth. The ratchet 130 is carried on shaft 139, having pinion 140 secured to its upper

end which meshes with rack 141 of carriage 142, so that the angular movement of ratchet 130, through the distance of one tooth, moves carriage 142 one letter space. The shaft 139 is surrounded by fixed cylinder 143, 70 within which is enclosed helical spring 144, one end of which is secured to cylinder 143 and the other end to shaft 139, so that when the spacing mechanism is operated, spring 144 is wound up and, on its release, carriage 142 is returned to its start position. 75

Shifting mechanism.

The shift mechanism for printing different sets of characters, represented by the 80 upper and lower case of the typewriter keyboard, is operated by means of rocking arm 145, secured to shaft 135, Fig. 11, being formed with two notches 146 and 147. The shift mechanism comprises two rocking arms 148, pivoted on to shaft 126, and bar 149, carried at the outer ends of arms 148. This bar is located underneath roller 150, of carriage 142. One of the arms 148 is provided with front extension 151, to which is pivoted, at 90 152, latch 153, the upwardly extending arm of which is provided with tooth 154, adapted to engage stationary lug 155, and normally to prevent the operation of the shift mechanism. 95

A spring 156 is connected to pin 157, of latch 153, and to a second pin 158, at the end of arm 159, of extension 151. The spring 156 normally holds tooth 154 in engagement with lug 155. A connecting rod 160 is pivoted to latch 153 and its lower free end is provided with pin 161, adapted to engage either of the notches 146 or 147, of bent arm 145. Intermediate its pivot and free end, connecting rod 160 has a pin 162, adapted to engage slot 163, of arm 164, which is secured to shaft 165, having its bearing in support 166. Also secured to shaft 165, Fig. 7, is arm 167, provided with pin 168. This pin is connected, by means of spring 169, to pull-bar 170, controlling the shift-mechanism and aligned with, and similarly operated as, type-bar-actuating pull-bars 69. The pull-bar 170 is formed with a bifurcated end, Figs. 7 and 11, in which the lower end of arm 164 is received. This pull-bar 170 is also provided with downward extension 171 and, when the pull-bar is moved to the right, as viewed in Fig. 11, L-shaped latch 172, engages behind extension 171, under tension of spring 173, surrounding pivot 174 of latch 172, and retains pull-bar 170 in its forward position. 115

The movement of pull-bar 170, puts arm 167 and shaft 165 under tension, through the action of spring 169, Fig. 7, and, as soon as bent arm 145 has been rotated sufficiently, to bring its notch 147 opposite pin 161, the lower end of connecting rod 160, snaps to the right to bring pin 161 into notch 147. 120 125 130

Then, when shaft 135 is rotated in the opposite direction, by spring 138, arm 145 pulls connecting rod 160 downwardly. When latch 153 is in its normal position, as shown in Fig. 11, there is a certain amount of lost motion between latch 153 and arm 148, to the extension of which it is pivoted, so that the first downward pull of connecting rod 160 releases tooth 154 from lug 155. The front end of latch 153 then rests against shaft 126, and latch 153, in conjunction with arms 148, move as a double-armed lever-unit about shaft 126 and cause bar 149 to lift roller 150 and carriage 142 for upper case printing.

15 An arm 175, Figs. 11 and 12, is secured to shaft 126, and when the shaft is rocked, as described, the lower end 176, of arm 175, engages behind adjustable latch plate 177, tiltably resting on fulcrum edge 178, and secured by means of set screws 179 to arm 180 which is pivoted at 181, while pin 182 at the lower end of arm 180, engages the notched end of the shift-release pull-bar 183, thereby retaining carriage 142 in its shifted position. A pair of set screws 184, 185, limit the movement of locking member 176.

When rocker arm 145 has reached its extreme downward limit of stroke, lever 186, secured to shaft 135, has reached its extreme forward position, Fig. 7, and, coming in contact with the laterally extending arm of L-shaped latch 172, rotates the latch about its pivot 174, thereby releasing extension 171 and permitting pull-bar 170 to return under tension of spring 187, carrying with it connecting rod 160 and arm 164, thereby disengaging pin 161 from notch 147 and returning all parts to normal position. In order to restore carriage 142 to its normal lower case position, it requires a separate code signal which brings about the operation of shift-release pull-bar 183, Fig. 12, which, being thrown forward, rotates arm 180 about its pivot 181, releases latch 176 of lever 175, from latch plate 177, thereby permitting carriage 142 to drop to its normal lower case position.

Carriage return mechanism.

50 The carriage return pull-bar 189, Fig. 15, is not moved longitudinally, like the other pull-bars, but simply tilted about a pivot located midway its length, for the reason that universal operating bar 96 is provided with slot 190, which comes beneath this pull-bar, when universal bar 96 is rocked to the right, as viewed in Fig. 15, whereby pull-bar 189 merely drops into the aligned notches of selector bars 67. Roller 95 gliding along arch 98 causes the forward end of pull-bar 189 to drop into the aligned notches, its rear end 191 is lifted and, being in engagement with bell crank 192, Fig. 14, rocks the same about its pivot 193. This bell crank carries at the 65 end of its second arm, pin 194, which en-

gages upper arm 195 of a double-armed lever, pivoted at 196. The lower arm 197 of this lever is formed with detent 198, Figs. 14 and 17, adapted to engage shoulder 199, formed on disc 200, secured to shaft 135. 70 Pivot 196 is mounted at the end of arm 201, secured to shaft 202, on which is also fastened forked member 203, the forked ends of which are located under ratchet 130 and are in contact with the lower face thereof. This lower face of ratchet 130 carries crown-toothed member 204, adapted to engage the teeth of a similar crown-toothed member 205, fixed to shaft 139.

When the energization of solenoid 31, Fig. 1, causes the rocking of shaft 135, in an anti-clockwise direction, shoulder 199 of disc 200 engages detent 198, pulls the same downward and rocks arm 201, causing the lifting of the prongs of forked member 203. This member, in turn, raises ratchet 130 and disengages the teeth of clutch 204 from those of clutch 205, permitting shaft 139 to rotate under the influence of spring 144 and thus returning the carriage 142, to its initial position, through the rotation of pinion 140, in mesh with rack 141. The rocking of shaft 202 causes arm 206 to swing to the right, as viewed in Figs. 14 and 16, permitting it to become engaged by notch 207, on latch 208, thereby holding ratchet 130 in raised position.

This latch 208 is linked, by means of connecting rod 209, to lever arm 210 carried on shaft 211, Fig. 14. A lever arm 212, secured to shaft 211, is adapted to engage pin 213 carried at one end of carriage 142, Figs. 7 and 10. When latch 208 engages lever arm 206, lever arm 212 is rotated in a clockwise direction about its pivot 211. When now carriage 142 approaches the end of its travel to the left, Figs. 10 and 14, pin 213 engages the end of lever 212, thereby lifting connecting rod 209 and latch 208, whereby the latter releases arm 206 and permits ratchet 130 to drop and to re-engage toothed clutch members 204 and 205 to normal relation.

Line feed mechanism.

The line feed is brought about by the rocking of two-notched bent arm 214, secured to shaft 135, Fig. 1. The parts associated with this arm are preferably operated in a similar manner, as the parts operated by arm 145 of the shift mechanism, shown in Fig. 11. The movement of arm 214 pulls connecting rod 215, in the same manner, as arm 145 pulls connecting rod 160. The upper end of connecting rod 215 is linked, at 216, to glide bar 217, movable along suitable guides 218. A roller 219 is provided at the upper end of guide members 217, which engages plate 220, extending the entire length of the carriage, being suitably pivoted on shaft 221, as shown in the above mentioned application. 115 120 125 130

On shaft 100, Figs. 7 and 12, similar to shaft 165 of the shift mechanism, Fig. 11, is secured arm 101, provided at the lower end with pin 102 and located between the bifurcated ends of the line-feed pull-bar 103, Fig. 13. This pull-bar 103 is connected to arm 101, by means of spring 104. A downward extension 105 of pull-bar 103, is adapted to be engaged by latch arm 106, whose releasing movement is controlled by arm 134, of shaft 135, similar to the release of the carriage-shift pull-bar 170, already described, whereby line-feed pull-bar 103, is also returned to normal.

It is to be understood that the mechanical functions mentioned in the claims, beside the printing, include, the spacing, the ribbon feeding, the holding down the inking ribbon, so that the printed characters are visible, except at the moment of printing, the carriage return, the carriage shift and unshift, the line feed, the auto signaling, etc. and similar mechanical functions, all of which are under the control of the selecting mechanism and result from positive and momentary operation of the single operating magnet.

What is claimed as new, is:—

1. The combination with selector magnets, of a controlling magnet, and means controlled by said selector magnets for preventing operation of the armature of said controlling magnet.

2. In a selecting mechanism, a plurality of selecting means, an operating means, locking means to lock said selecting means in selected position, locking means to lock said operating means in unactuated position, and connecting means between said locking means whereby said operating means is freed for actuation when any one of said selecting means is actuated.

3. In a selecting mechanism, a plurality of selecting means, a locking means for each of said selecting means, an operating means, and a locking means for said operating means under the control of any one of said selecting means.

4. In a selecting mechanism, a plurality of selecting means, a locking means for each of said selecting means, an operating means, and a locking means for said operating means under the control of any one of said first mentioned locking means.

5. In a selecting mechanism, a plurality of selecting magnets, a locking means for each of said selecting magnets, an operating magnet, a locking means for said operating magnet, and interconnecting means between all of said locking means whereby when any one of said first mentioned locking means operates to lock its selecting magnet, said operating magnet is freed for actuation.

6. In a selecting mechanism, a plurality

of selecting means, locking means for said selecting means, an operating means, locking means for said operating means, and means controlled by said operating means to release said first mentioned locking means and to condition said second mentioned locking means to lock said operating means.

7. In a selecting mechanism, a plurality of selecting magnets, locking means for said selecting magnets, an operating magnet, locking means for said operating magnet, and means controlled by said operating magnet to release said first mentioned locking means and to condition said second mentioned locking means to lock said operating means.

8. A selecting mechanism comprising a plurality of selecting magnets, armatures for said selecting magnets, a latch to hold each of said armatures in energized position, an operating magnet, an armature for said operating magnet, a latch to hold said armature in de-energized position, a trip for said last mentioned latch, and a bar connected to said first mentioned latches and carrying said trip.

9. A selecting mechanism comprising a plurality of selecting magnets, armatures for said selecting magnets, a latch to hold each of said armatures in energized position, an operating magnet, an armature for said operating magnet, a latch to hold said armature in de-energized position, a trip for said last mentioned latch, a bar connected to said first mentioned latches and carrying said trip, an extension on said operating magnet armature, and an extension on said bar, said first mentioned extension co-acting with said second mentioned extension to move said bar and to restore all of said latches to a non-selective position.

10. In a selecting mechanism, a plurality of selecting means and movable selector bars adapted to be selected by said selecting means, said selector bars being movable only in the direction of their length to make a selection and adapted to remain in their last selected position until another position is required by a subsequent selective operation.

11. In a selecting mechanism, a plurality of selecting means, and a plurality of movable selector members controlled by said selecting means, said selector members being movable only in the direction of their length to make a selection and normally remaining in a given position until a different position is required in a subsequent selective operation.

12. In a selecting mechanism, a plurality of selecting means and a plurality of movable selector members controlled by said selecting means, each of said selector members containing a plurality of slots to be aligned in various combinations, and each member adapted to remain in its last se-

lected position until a new position is required in a subsequent selective operation.

13. In a selecting mechanism, a plurality of selecting means and a plurality of movable selector bars controlled by said selecting means, each of said selector bars containing a plurality of slots to be aligned in various combinations, and each bar adapted to remain in its last selected position until a new position is required in a subsequent selective operation.

14. In a selecting mechanism, a plurality of selecting means, a plurality of transfer and storage members controlled by said selecting means, and a plurality of selector bars controlled by said storage members, said selector bars being movable only in the direction of their length for selective purposes and adapted to remain in their last selected position until a different position is required in a subsequent selective operation.

15. In a selecting mechanism, a plurality of selecting means, a plurality of transfer and storage members controlled by said selecting means, and a plurality of selector members moved to selected positions by said transfer and storage members, each of said selector members containing a plurality of slots to be aligned in various combinations for selective purposes and each selector member adapted to remain in its last selected position until a different position is required in a subsequent combination.

16. In a selecting mechanism, a plurality of selecting means, a plurality of transfer and storage members controlled by said selecting means, and a plurality of selector bars moved to selected positions by said transfer and storage members, each of said selector bars containing a plurality of slots to be aligned in various combinations for selective purposes and each selector bar adapted to remain in its last selected position until a different position is required in a subsequent combination.

17. In a selecting mechanism, a plurality of selecting means, an operating means, a plurality of transfer and storage members controlled by said selecting means, a movable carrier for said transfer and storage means controlled by said operating means, a plurality of selector controlling members controlled by said transfer and storage members and movable selector members controlled by said selector controlling members.

18. In a selecting mechanism, a plurality of selecting means, an operating means, transfer and storage means controlled by said selecting means, a carrier for said transfer and storage means controlled by said operating means, a plurality of selector members and selector member controlling means controlled by said transfer and storage means.

19. In a selecting mechanism, a plurality

of selecting magnets, an operating magnet, transfer and storage means controlled by said selecting magnets, a carrier for said transfer and storage means controlled by said operating magnet, a plurality of selector members, and selector member controlling means controlled by said transfer and storage means.

20. In a selecting mechanism, a plurality of selecting means, an operating means, transfer and storage means controlled by said selecting means, a movable carrier for said transfer and storage means, a power storage device tending to propel said movable carrier, a plurality of movable selector bars, and releasing means for said power storage device, under the control of said operating means to permit propulsion of said movable carrier to set said movable selector bars.

21. In a selecting mechanism, a plurality of selecting magnets, an operating magnet, a plurality of transfer and storage members controlled by said selecting magnets, a movable carrier for said transfer and storage member, a spring actuated driving member for said carrier, releasing means under the control of said operating magnet to permit said driving member to actuate, said carrier, and a restoring means to condition said driving means and said carrier for a subsequent selective operation.

22. In a printing telegraph machine, a selecting mechanism, type carrying means, actuating means controlling said type carrying means, and operating means, said actuating means comprising curved surfaces adapted to co-act with said operating means to permit said actuating means to engage said selecting mechanism without shock.

23. In a printing telegraph machine, a selecting mechanism, type carrying means, actuating means controlling said type carrying means, and operating means, said actuating means comprising projections and curved surfaces adapted to co-act with said operating means to permit said actuating means to engage said selecting means gradually and to complete a printing operation in one movement of said operating means.

24. In a printing telegraph machine a selecting mechanism, type carrying means comprising projections and curved surfaces and operating means co-acting with said actuating means to permit selection and complete an operation of said actuating means on a forward movement of said operating means, and on a return movement of said operating means co-acting to restore said actuating means.

25. In a printing telegraph machine, a selecting mechanism, a plurality of type carrying bars, selectable actuating bars connected to said type carrying bars each actuating bar carrying a curved surface, and

an operating frame carrying an operating member, said curved surfaces and said operating member co-acting to gradually permit said actuating bars to move substantially without shock into selected position and restore to non-selected position.

26. In a printing telegraph machine, a selecting mechanism, a plurality of type carrying bars, selectable actuating bars connected to said type carrying bars, each actuating bar carrying a curved surface, and an operating frame carrying a roller shaped member, said curved surfaces and said roller shaped member coacting to gradually permit said actuating bars to move substantially without shock into selected position and restore to non-selected position.

27. In a printing telegraph machine, a selecting mechanism, a plurality of type bars, selectable actuating bars connected to said type bars, each actuating bar carrying a projection and a curved surface, and an operating frame carrying an operating member and a universal bar, said actuating bar and said operating frame co-acting to gradually permit said actuating bars to move into selected position substantially without shock and complete an operation of a selected actuating bar in one movement of said frame, and on a return movement of said frame co-acting to restore said actuating members to nonselected position.

28. In a printing telegraph machine a selecting mechanism, a plurality of type bars, selectable actuating bars connected to said type bars, each actuating bar carrying a projection and a curved surface, and an operating frame carrying a roller shaped member and a universal bar, said actuating bar and said operating frame co-acting to gradually permit said actuating bars to move into selected position substantially without shock and complete an operation of a selected actuating bar in one movement of said frame, and on a return movement of said frame co-acting to restore said actuating members to nonselected position.

29. A printing telegraph machine comprising a plurality of type-bars; a movable platen coacting with said type bars; a plurality of actuating bars controlling said type-bars; a selecting mechanism responsive to received code combinations of selecting conditions embodying a plurality of notched selector bars selectively controlling said actuating bars; operating means for said actuating bars; a spacing mechanism, and mechanical devices actuated by said operating means for conditioning said spacing mechanism for operation during a printing movement of said type bars and for operating the same during a restoring movement of said type bars.

30. A printing telegraph machine comprising a plurality of type bars; a plurality of

actuating bars controlling said type bars; a selecting mechanism responsive to received code combinations of electrical conditions controlling said actuating bars; a common operating bail structure for said actuating bars; and a spacing mechanism condition for operation during a printing movement of said actuating bail structure; and operated by said structure during a restoring movement thereof.

31. In a printing telegraph machine, a selecting mechanism, type-carrying means, selectable actuating means controlling said type-carrying means, movable operating means for said actuating means, and a spacing mechanism partially operated by a first movement of said operating means and completely operated by a second movement of said operating means.

32. In a printing telegraph machine a selecting mechanism, a plurality of type-bars, selectable actuating bars connected to said type bars, a printer operating means, and a spacing mechanism partially operated by a printing stroke of said operating means through the medium of said type bars, and completely operated by a return stroke of said printing means.

33. In a printing telegraph machine, a selecting mechanism, type-carrying means, selectable actuating means controlling said type carrying means, a printing magnet controlling said actuating means, and a spacing mechanism completely actuated through solely mechanical connection by the combined energization and de-energization of said printing magnet.

34. In a printing telegraph machine, a selecting mechanism, a plurality of type bars, selectable actuating bars controlling said type bars, a printing magnet controlling said actuating bars, and a spacing mechanism comprising a universal bar controlled by said type bars and a ratchet mechanism partially operated by said universal bar and completely operated through direct mechanical connection by de-energization of said printing magnet.

35. In a printing telegraph machine, a selecting mechanism, a plurality of type bars, selectable actuating bars controlling said type-bars, printing means controlling said actuating bars, a universal bar actuated by said type bars, a pawl lever carrying a plurality of pawls and a ratchet wheel operated by said pawls, said universal bar operating to advance said pawls and said printing means operating independently of said universal bar to restore said pawls and advance said ratchet wheel.

36. In a printing telegraph machine, a selecting mechanism, a printing mechanism controlled by said selecting mechanism, a movable operating means controlling said printing mechanism, and a case shift mecha-

- nism conditioned for actuation by one movement of said operating means, and actuated by another movement of said operating means.
- 5 37. In a printing telegraph machine, a selecting mechanism, type carrying means, selectable actuating means controlling said type carrying means, movable operating means for said actuating means, and a case shift mechanism, said operating means being adapted to partially operate said shift mechanism by a first movement and to completely operate said shift mechanism by a second movement.
- 10 38. In a printing telegraph machine a selecting mechanism, a plurality of type bars, selectable actuating bars controlling said type bars, a printing magnet controlling said actuating bars, and a case shift mechanism including a selectable shift pull bar, said shift pull bar, upon selection, being actuated by an energizing stroke of said printing magnet to condition said shift mechanism for complete actuation by a de-energizing stroke of said printing magnet.
- 15 39. In a printing telegraph machine, a selecting mechanism, type carrying means, selectable actuating means controlling said type carrying means, a printing magnet controlling said actuating means, and a case shift mechanism actuated through solely mechanical connection by the combined energization and de-energization of said printing magnet.
- 20 40. In a printing telegraph machine, a selecting mechanism, a plurality of type bars, selectable actuating bars controlling said type bars, a printing magnet controlling said actuating bars, and a shift mechanism comprising a selectable shift actuating bar, a shift frame and latch, an operating member controlling said shift frame and latch and controlled by said shift actuating bar, said printing magnet being adapted on an energizing movement to actuate said shift actuating bar to condition said operating member for actuation, and on a de-energizing movement to actuate said operating member to complete a shift operation.
- 25 41. In a printing telegraph machine, a selecting mechanism, a printing mechanism, a case shift mechanism including a movable frame and an extension on said frame, and a case shift lock adapted to engage said extension comprising a pivotally mounted member with an adjustable latch plate thereon.
- 30 42. In a printing telegraph machine, a selecting mechanism, a printing mechanism, a case shift mechanism including a movable frame and an extension on said frame, and an adjustable means co-acting with said extension to definitely limit movement of said frame.
- 35 43. In a printing telegraph machine, a selecting mechanism, a printing mechanism, a case shift mechanism including a movable frame and an extension on said frame, and a case shift latch adapted to engage said extension and limit intermediate movement of said frame.
- 40 44. In a printing telegraph machine, a selecting mechanism, a printing mechanism, a case shift mechanism including a movable frame and an extension on said frame; a support, adjustable means mounted on said support co-acting with said extension to limit extreme movement of said frame, and a pivoted member mounted on said support, an adjustable latch plate tiltably mounted on said pivoted member, said latch plate co-acting with said extension to retain said shift mechanism in shifted position.
- 45 45. In a printing telegraph machine, a selecting mechanism, a printing mechanism, an operating means controlling said printing mechanism, a case shift mechanism, a case shift lock comprising a pivotally mounted member supporting a tiltably mounted latch, and a shift release pull bar connected to said pivotally mounted member and controlled by said selecting mechanism and said operating means.
- 50 46. In a printing telegraph machine, a selecting mechanism, a printing mechanism controlled by said selecting mechanism, a movable operating means controlling said printing mechanism, and a carriage return mechanism conditioned for actuation by one movement of said operating means and actuated by another movement of said operating means.
- 55 47. In a printing telegraph machine, a selecting mechanism, type carrying means, selectable actuating means controlling said type carrying means, a movable operating means for said actuating means, and a carriage return mechanism, said operating means being adapted to partially operate said return mechanism by a first movement completely operate said return mechanism by a second movement.
- 60 48. In a printing telegraph machine, a selecting mechanism, type-carrying means, selectable actuating means controlling said type-carrying means, a printing magnet controlling said actuating means, and a carriage return mechanism actuated through solely mechanical connection by the combined energization and de-energization of said printing magnet.
- 65 49. In a printing telegraph machine, a selecting mechanism, a plurality of type-bars, selectable actuating bars controlling said type bars, a printing magnet controlling said actuating bars, and a carriage return mechanism including a selectable carriage return control bar; said control bar, upon

selection, being actuated by an energizing stroke of said printing magnet to condition said carriage return mechanism for complete actuation by a de-energizing stroke of said printing magnet.

50. In a printing telegraph machine, a selecting mechanism, a plurality of type-bars, selectable actuating bars controlling said type bars, a printing magnet controlling

10 said actuating bars, and a carriage return mechanism comprising a selectable control bar, an operating member actuated by said control bar, and a clutch member controlled by said operating member; said printing 15 magnet being adapted by an energizing movement to permit actuation of said control bar to condition said operating member for actuation by a following de-energizing movement of said printing.

20 51. In a printing telegraph machine, a selecting mechanism, a printing mechanism, a movable carriage, a carriage return mechanism comprising a selectable control bar, operating means actuated by said control 25 bar, a clutch control member, a latch to lock said clutch control member in disengaging position, and means controlled by said carriage to disengage said latch and permit restoration of said clutch control member 30 to engaging position.

52. In a printing telegraph system, a selecting mechanism, a printing mechanism, a movable carriage, stepping means for moving said carriage in one direction, power 35 storing means actuated by said stepping means, a clutch connecting said power storing and said stepping means, a selectable control bar, operating means actuated by said control bar, a clutch operating member, 40 a latch co-acting with said clutch control member to lock said clutch in disengaged position to permit said power storing means to restore said carriage and means controlled by said carriage return to release said clutch 45 control member and permit return of said clutch to engaged position.

53. In a printing telegraph system, a selecting mechanism, a printing mechanism, movable operating means controlling said 50 printing mechanism, a movable carriage stepping means controlling said carriage, power storing means operated by said stepping means, a normally engaged separable connection between said stepping and said 55 power storing means, a control bar controlled by said selecting mechanism, means for disengaging said separable connection conditioned for actuation by said control bar, and actuated by said movable operating 60 means, a pivotally supported latch to retain said separable connection in disengaged position, and means for releasing said latch actuated by the return movement of said carriage.

54. In a printing telegraph machine, a selecting mechanism, a printing mechanism controlled by said selecting mechanism, a movable operating means controlling said printing mechanism, and a line feed mechanism conditioned for actuation by one 65 movement of said operating means, and actuated by another movement of said operating means.

55. In a printing telegraph machine, a selecting mechanism, type-carrying means, 70 selectable actuating means controlling said type carrying means, movable operating means for said actuating means, and a line feed mechanism, said operating means being adapted to partially operate said line feed 75 mechanism, by a first movement, and completely operate said feed mechanism by a second movement.

56. In a printing telegraph machine, a selecting mechanism, a plurality of type-bars 80 selectable actuating bars, controlling said type-bars, a printing magnet controlling said actuating bars, and a line feed mechanism including a selectable feed operating bar, 85 said operating bar when selected being actuated by an energizing stroke of said printing magnet to condition said feed mechanism for complete actuation by a de-energizing stroke of said printing magnet.

57. In a printing telegraph machine, a selecting mechanism, type-carrying means, selectable actuating means controlling said type carrying means, a printing magnet controlling said actuating means, and a line feed mechanism actuated through solely mechanical connection by the combined energization and de-energization of said printing magnet.

58. In a printing telegraph machine, a selecting mechanism, a plurality of type bars, selectable actuating bars controlling said type-bars, a printing magnet controlling said actuating bars, a selectable line feed operating bar and a latch to retain said operating bar in actuated position, said printing magnet being adapted on an energizing stroke to 100 actuate said operating bar when selected, and on de-energizing stroke to restore said latch, thereby permitting restoration of said actuated operating bar.

59. In a printing telegraph machine, a selecting mechanism, a printing mechanism, a line feed operating bar, a selectable line feed actuating bar, and a power storage means connecting said operating bar and said 110 actuating bar.

60. In a printing telegraph machine, a selecting mechanism, a printing mechanism, a line feed operating bar, a selectable line feed actuating bar, and a spring connecting said operating bar and said actuating bar.

61. In a printing telegraph machine, a selecting mechanism, a printing mechanism, a selectable line feed actuating bar, a line

- feed operating bar actuated by said line feed actuating bar, line feeding means actuated by said operating bar, and a latch adapted to retain said actuating bar and said operating bar in actuated position.
62. In a printing telegraph machine, a selecting mechanism, a printing mechanism, a selectable line feed actuating bar, a latch to retain said actuating bar in actuated position, and a releasing means for said latch.
63. In a printing telegraph machine, a selecting mechanism, a printing mechanism, operating means for said printing mechanism, a line feed actuating bar, controlled by said selecting means and actuated by said operating means, a latch to lock said actuating bar in actuated position, and a releasing means for said latch actuated by said operating means.
64. In a printing telegraph machine, a selecting mechanism controlled by code combinations of electrical impulses and actuated by selector setting means, a printing mechanism controlled by said selecting mechanism and adapted to perform a plurality of printing and a plurality of control operations, and a single electro-magnetic means, controlled by said selector setting means, supplying the entire actuating energy for said printing and said control operations.
65. In a printing telegraph machine, a selecting mechanism controlled by code combinations of electrical impulses and actuated by selector setting means, a printing mechanism controlled by said selecting mechanism and adapted to perform a plurality of printing and a plurality of control operations, and a single electro-magnetic means, controlled by said selector setting means, supplying the entire actuating energy for said printing and said control operations and for restoring said selecting mechanism after a selective operation.
66. In a printing telegraph machine, a selecting mechanism, a printing mechanism comprising a plurality of movable type-bars controlled by said selecting mechanism and adapted to perform a plurality of printing and stunt operations, and a single electro-magnetic means supplying all the necessary actuating energy for the complete operation of said printing mechanism.
67. In a printing telegraph machine, a selecting mechanism, a printing mechanism comprising a plurality of movable type-bars controlled by said selecting mechanism and adapted to perform a plurality of printing and stunt operations, and a single electro-magnetic means supplying all the necessary actuating energy for the complete operation of said printing mechanism and for restoring said selecting mechanism after a selective operation.
68. In a printing telegraph machine, a selecting mechanism, a printing mechanism controlled by said selective mechanism, and a single electro-magnet supplying the entire actuating energy necessary for complete operation of said printing mechanism.
69. A printing telegraph machine comprising a printing mechanism embodying a paper platen, a plurality of type bars coacting with said paper platen to effect printing of selected characters, control mechanism, and a plurality of actuating bars controlling said type bars; a selecting mechanism controlling said actuating bars; a common operating bail structure for said actuating bars; and a single electro-magnet supplying the actuating energy to said operating bail structure and said control mechanisms.
70. In a printing telegraph machine, a selecting mechanism, a printing mechanism controlled by said selective mechanism and adapted to perform a plurality of printing and stunt operations, and a single electro-magnet supplying all actuating energy necessary for complete operation of said printing mechanism.
71. In a printing telegraph machine, a selecting mechanism, a printing mechanism controlled by said selective mechanism and adapted to perform a plurality of printing and stunt operations, and a single electro-magnet supplying all actuating energy necessary for complete operation of said printing mechanism, and for restoration of said selecting mechanism.
72. In a printing telegraph machine, a selecting mechanism, a printing mechanism, a spacing mechanism, a carriage return mechanism, a line feed mechanism and a shift mechanism; and a single electro-magnetic means supplying and solely controlling all necessary actuating energy for the complete mechanical operation of said mechanisms.
73. In a printing telegraph machine, a selecting mechanism, a printing mechanism, a spacing mechanism, a carriage return mechanism, a line feed mechanism and a shift mechanism; and a single electro-magnet supplying and solely controlling all necessary actuating energy for the complete mechanical operation of said mechanisms.
74. In a printing telegraph machine, a selecting mechanism, a printing mechanism controlled by said selecting mechanism and a single electro-magnetic means supplying and solely controlling all energy necessary for complete mechanical actuation of said printing mechanism and restoration of said selecting means, following an operation of said selecting means.
75. In a printing telegraph machine, a selecting mechanism, a printing mechanism controlled by said selecting mechanism and a single electro-magnet supplying and solely

controlling all energy necessary for complete mechanical actuation of said printing mechanism and restoration of said selecting means, following an operation of said selecting means.

76. In a printing telegraph a selective mechanism responsive to code combinations of electrical conditions; a printing mechanism controlled by said selecting mechanism; operating means for said printing mechanism, a magnet; an armature for said magnet controlling said operating means; and means for permitting operation of said armature upon energization of said magnet only when said selective mechanism is actuated immediately preceding the energization of said magnet.

77. The combination as set forth in claim 76, in which said last mentioned means comprises a locking member for said armature controlled by said selecting means.

78. The combination as set forth in claim 76, in which said last mentioned means comprises a locking member for said armature controlled by said selecting means, and in which said locking member is moved to permit operation of said armature whenever a selection is set up on said selective mechanism.

79. In a printing telegraph a selective mechanism responsive to code combination of electrical conditions comprising a plurality of selector members each embodying a plurality of slots and adapted to be moved in various combinations to selectively align said slots; a printing mechanism comprising a plurality of actuating bars selectable by movement into said aligned slots and a plurality of type bars operated by said actuating bars; operating means for said actuating bars; an operating magnet; an armature for said operating magnet controlling said operating means; and locking means for preventing operation of said armature upon energization of said operating magnet until said selecting mechanism has been actuated in response to a code combination of conditions.

80. The combination as set forth in claim 79 in which said operating means comprises a printing magnet controlled by said operating magnet.

81. The combination as set forth in claim 79 in which said selective mechanism comprises a selector magnet individual to and controlling each of said slotted selector members, together with means operated by any one of said selector magnets for operating said locking means to permit operation of said armature by the energization of said operating magnet.

82. A printing telegraph machine comprising electro-responsive means; selecting mechanism controlled by said electro-responsive means; printing mechanism con-

trolled by said selecting mechanism; a longitudinally movable carriage mechanism embodying a rotatable platen coacting with said printing mechanism, and a spacing rack; a spacing drive pinion engaging said spacing rack; a ratchet wheel for driving said pinion; a stepping pawl spring pressed into engagement with said ratchet wheel; a reciprocating member upon which said stepping pawl is pivotally mounted; common power means for actuating said mechanisms; and solely mechanical means actuated by said power means and adapted to reciprocate said slidale member to actuate said pawl and cause stepping of said carriage.

83. The combination as set forth in claim 82, in which said last mentioned means causes said slidale member to advance said pawl over the teeth of said ratchet during a printing stroke of said printing mechanism and to actuate said pawl to rotate said ratchet wheel after the printing stroke has been completed.

84. A selecting mechanism comprising a plurality of selectable members; a plurality of selecting members movable in various combinations to selectively control said selectable members; a three armed pivoted actuating member individual to each of said selecting members; and means responsive to received code combinations of selecting conditions adapted to engage either one of a pair of arms of said three armed members to effect selecting movements of said selectable members in accordance with the received code combinations.

85. In a printing telegraph machine, a selecting mechanism responsive to code combinations of electrical conditions; a plurality of actuating bars controlled by said selecting mechanism; a plurality of type bars controlled by said actuating bars; operating means for said actuating bars to effect printing strokes of selected ones of said type bars; a paper carriage comprising a rotatable platen, coacting with said type bars; a spacing mechanism; and means for initiating restoration to unacted position of any of said type bars that stick in actuated position.

86. The combination as set forth in claim 85, in which said last mentioned means comprises means actuated by said operating means.

87. The combination as set forth in claim 86 in which said operating means actuates said last mentioned means through said spacing mechanism to initiate restoration of stuck ones of said type bars.

88. In a printing telegraph machine, a selecting mechanism; a printing mechanism controlled by said selecting mechanism; actuating means for effecting a printing stroke of said printing mechanism; means for re-

- storing said printing mechanism after a printing stroke; and means for forcibly initiating the restoration of said printing mechanism in event of said restoring failing to effect said restoration. 5
89. The combination as set forth in claim 88 in which said last mentioned means comprises a spacing mechanism for said printing mechanism operated by said actuating 10 means. 60
90. The combination as set forth in claim 69 in which said control mechanism comprise spacing, carriage return, and line feed mechanisms. 65
91. In a printing telegraph machine a plurality of type bars; a plurality of actuating bars controlling said type-bars; a plurality of notched permutation members controlling said actuating bars; a corresponding set of actuating devices operative in each of two conditions for shifting the corresponding permutation member from one of two positions to the other; means for reciprocating said actuating devices to effect 70 the operation thereof upon said permutation members; and electromagnetic means for determining the operative conditions of said actuating devices in response to received code combinations. 75
92. In combination, in a telegraph receiver, a plurality of selectable devices, printing means controlled thereby, a set of notched permutation members, a corresponding set of transfer and storage members adapted to 80 shift said permutation members in opposite directions to align the notches thereof and thereby control said selectable devices, said transfer and storage members being operative upon said permutation members only 85 when the latter are to be moved to positions differing from those occupied at the preceding selecting operations, and electromagnetic means for controlling said transfer and storage members in response to received code combinations. 90
93. In a printing telegraph receiver, a plurality of type bars, corresponding actuating bars, a set of longitudinally movable, notched permutation bars, a corresponding 95 set of actuating devices operative in different conditions to shift said permutation members in opposite directions, to align the notches thereof and thereby selectively control said actuating bars, means for reciprocating said actuating devices to effect the 100 operation thereof upon said permutation bars, a common operating member for moving the selected actuating bars through the notches of the permutation bars to operate 105 the corresponding type bars, and electromagnetic means controlling the setting of said actuating devices in response to received code combinations. 110
94. A selecting mechanism comprising a set of notched permutation members, pivoted levers individual to said permutation members and connected thereto, a set of actuating devices operative in two different conditions upon said levers to shift the same and the corresponding permutation members 115 in opposite directions, means for reciprocating said actuating devices to effect the operation thereof upon said levers, and electromagnetic means for selectively determining the operative conditions of said actuating devices in response to received code combinations. 120
95. A selecting mechanism for telegraph receivers comprising a set of notched permutation members movable in opposite directions to selectively align the notches thereof, a plurality of selectable members controlled by the alignment of the notches of said permutation members, pivoted levers individual to said permutation members and operatively connected thereto, a corresponding set of transfer and storage devices for said levers, means for moving said transfer and storage devices through two different paths to tilt said levers and thereby move the corresponding permutation members in opposite directions and electro-magnetic means for determining the operative conditions of said actuating devices in response to received code combinations. 125
96. In combination in a printing telegraph receiver, a set of notched permutation members, a corresponding set of actuating members adapted to be set in response to received code combinations and each operative in two different conditions for shifting the corresponding permutation members in opposite directions to selectively align the notches thereof, printing means, a plurality of devices controlling the operation of said printing means, said devices being selectable by lateral movement into the aligned notches of said permutation members and operating means for successively shifting the said actuating members to effect the operation thereof upon said permutation members, effecting the engagement of said controlling devices with said permutation members and the operation of said printing means. 130
